AUTOMATIC GAS SHUT-OFF VALVE

Application filed March 8, 1930. Serial No. 434,204.

This invention relates to gas valves and more particularly to an automatic gas shut off valve adapted for use at the consumer or low pressure end of a gas line to automatically terminate the flow of gas to the consumer whenever the pressure in the line has fallen below a predetermined minimum.

It is well known in the gas industry that if the pressure of gas in a gas distribution system should fall below a predetermined minimum whether it be due to inadvertance or an act of God, the flames of the consumer's gas appliances are apt to go out and obviously when the pressure in the distribution system is restored gas will continue to flow from such appliances and thereby put the lives and property of the consumer in jeopardy.

It is in view of the above mentioned danger that the gas producing concerns whenever they shut off the flow of gas in the distribution main or when the flow of gas drops below a predetermined minimum, find it necessary to send out men to homes of consumers for the purpose of warning the consumers to shut off the flames of their gas appliances such as a pilot flame in a burner, the flame in an illuminating device and the like. Obviously, this procedure entails a great deal of expense to the gas producer and more important still the system used is haphazard since the men sent out to check up on the consumers to make sure that gas will not escape from any of their appliances when the gas pressure is restored, may overlook some of the appliances or may even overlook calling on some of the consumers.

Various attempts have been made to solve this situation by providing automatic shut off valves at the consumers' ends of the distribution system, but these attempts have not proven very successful or satisfactory inasmuch as such shut off valves have usually been highly expensive to make and cannot always be readily adapted for use in connection with the apparatus at present in use with gas distribution systems.

It is an object of this invention to provide a greatly simplified gas shut off valve of inexpensive construction and readily adapted

for use with the conventional apparatus used in gas distribution systems, and adapted to automatically shut off the flow of gas to the consumer when the pressure of the gas at the consumer's end of the distribution line falls below a predetermined minimum and to remain shut until manually reset.

In accordance with the general features of the present invention there is provided a gas shut off valve including a diaphragm 60 chamber having an inlet for connection to the gas main at the discharge side of the usual low pressure regulator at the consumer's station, and an outlet for connection to the consumer's supply line, there being a 65 well of mercury around the inlet for the valve cooperable with a cup secured to a weighted diaphragm in the chamber which diaphragm is movable under the effect of the weight when the pressure in the chamber drops below a predetermined minimum to cause the cup to enter the well of mercury for the purpose of shutting off the supply of gas to the chamber from the gas distribution main.

Another feature of the invention relates to 75 the provision of a highly simplified shut off valve of the above described character in which only a portion of the diaphragm is subjected to the incoming gas pressure once the valve is closed whereby the weight on the 80 diaphragm will maintain the valve shut until the valve is manually reopened.

Other objects and advantages of this invention will more fully appear from the following detailed description taken in connection 85 with the accompanying drawing which illustrates the single embodiment thereof, and in which;

Figure 1 is a plan view of the shut off valve;

Figure 2 is a vertical sectional view through the valve showing the position of the parts of the valve when it is in its opened position; and

Figure 3 is a view similar to Figure 2 showing the valve in its closed position.

The reference character designates generally a housing formed to provide a pressure chamber 11 partly defined by a diaphragm 12 having its peripheral edge secured to a 100

bowl-shaped housing 10 by means of a top or cover 13 secured to the housing 10 by bolts 15 extending through suitable openings in the marginal portion of the diaphragm 12. The space in the cover 13 above the diaphragm 12 is connected to the atmosphere by means of a vent pipe 16 so as to prevent compression of the air in the cover above the diaphragm.

10 The cover 13 is provided with a central enlargement or boss 17 which serves as a guide for a stem 18 having one end secured to the center of the diaphragm 12. The other end of the stem 18 extends into a thimble-shaped cap 19 removably enveloping the boss 17.

Surrounding the stem 18 disposed on top of the diaphragm 12 is a weight 20 which is of a predetermined size and is calibrated to be in proportion to the pressure of the gas 20 normally prevailing in the chamber 11.

Secured to the underside of the diaphragm 12 directly below the weight 20 and the valve stem 18 is an inverted cup 21 adapted upon the depression of the valve stem 18 due to 25 a drop in the gas pressure prevailing in the chamber 11 to enter a well 22 formed integral with the housing 10 and shaped to receive a sealing liquid, such, for example, as mercury, designated by the reference character 30 ter 23.

The housing has formed integral with it a laterally and downwardly projecting fin or extension 24 terminating at one end in the well portion 22. This extension 24 has 35 formed in it a Z-shaped gas inlet passageway 25 terminating at its inner end in an upwardly extending tube 26 formed integral with the well portion 22. This tube 26 extends through the well and is surrounded by 40 the mercury 23.

The extension 24 is also provided with an outlet passageway 28 having one end in communication with the chamber 11 and having its other end threaded to receive a pipe leading 45 to the consumer's appliances.

The operation of this shut off valve of our invention is briefly as follows:

Normally, when the gas is of proper pressure in the distribution main, the valve will 50 be in its open position as shown in Figure

2. When in this position gas is drawn by the consumer upon the lighting of one of his appliances through the valve from the conventional pressure regulator usually used in each 55 consumer's station. However, if for any reason at all the pressure should drop below a predetermined point or the gas should stop flowing entirely, the pressure in chamber 10 will be dissipated immediately upon the consumer lighting one of his appliances or by an appliance that is already lit and operating 60 at the time the pressure of the gas drops.

The drop in pressure of the gas in the chamber 10 will result in the diaphragm 12 being 65 depressed by the weight 20 to the position

shown in Figure 3, in which position the valve is closed.

Incidentally, it is to be noted that if the pressure in the distribution main drops only temporarily and the gas pressure in the main is returned to normal before the consumer draws any gas from the valve chamber, then the pressure in the chamber 11 is not affected and the diaphragm obviously will not be depressed. In other words, it is only when the customer is actually consuming gas and drawing it from the chamber 11 of the valve that this valve will become effective to immediately shut off the supply of gas upon a drop of the pressure of the gas below a predetermined point. This is advantageous to the extent that this shut off valve does not come into play unless gas is being consumed at the time that the pressure is below the predetermined point at which the valve is set to operate. This means that not all of the gas valves at the consumers' stations will be shut upon a drop in gas pressure but only those from which the gas pressure in the chamber of the valve is depleted. Therefore, if the drop in pressure is only temporary and the consumer has not been drawing gas during that period, this gas valve remains unaffected.

When the gas valve is in its closed position the inverted cup 21 extends down into the ring of mercury 23. Thereafter, the entire surface of diaphragm 12 is not subjected to the gas pressure but only has that portion of its area defined by the cup 21 exposed to the incoming gas pressure. In other words, upon the gas being restored to its normal pressure, this gas will flow through the passageway 25 and will come in contact with only the top of the inverted cup 21 which has a relatively small area as compared with the total area of the diaphragm 12. The gas is prevented from entering the chamber 11 by the column of mercury 23 in the well 22 which acts as a seal. Now the weight 20 is so calibrated that it will exert a greater force on the diaphragm 12 than the force being exerted upon the diaphragm by the gas in the cup 21 when the valve is in its closed position, and as a result this weight will keep the valve in its closed position.

Upon the consumer finding out that the supply of gas has been shut off, he will immediately notify the gas company which will send out a man to reopen the shut off valve. This eliminates the necessity of the company sending out men to all of the homes of their consumers since these gas valves will prevent gas from escaping at any one consumer's home upon a sudden drop in the gas pressure below the predetermined point at which the shut off valve is set to close.

The valve may be readily opened by merely removing the cap 19 and pulling the diaphragm upwardly by its stem 18, thus drawing the inverted cup 21 out of the mercury

well and allowing gas to again flow into the chamber 11. The stem 18 also serves to guide the diaphragm in its movement so as to insure that the cup 21 will be aligned with the tube 26 and hence properly enter the well of mercury.

It will also be observed that the housing 10 has an internal slanting surface directly over the inlet 25 terminating at its lower end 10 in the well 22 and at its upper end in communication with the outlet 28 so that mercury may be introduced into the well from the outlet without the necessity of removing the cover and diaphragm from the housing.

Now we desire it understood that although we have illustrated and described in detail the preferred embodiment of our invention, the invention is not to be thus limited but only insofar as defined by the scope and spirit of the appended claim.

We claim as our invention:

A gas shut-off valve, comprising a bowl-shaped member having a laterally extending integrally formed fin or extension on the 25 lower side thereof, said fin having a T-shaped

terminal portion for connection in a gas riser to provide support for said valve in a horizontal position, said fin having an annular well in the bottom wall of the bowl to receive a sealing fluid cooperable to seal the gas inlet to the bowl, said fin being passaged to provide a gas inlet through the bottom of said bowl and also being passaged to provide a gas outlet conduit above said gas inlet passage opening into said bowl through the side 75 thereof and above the bottom thereof, a diaphragm on said bowl forming a closure therefor, an inverted cup-shaped member secured on the lower side of said diaphragm and in alignment with the recess to cooperate with a sealing fluid in the recess to close the gas inlet to the bowl, a cover on said bowl, and a stem on said diaphragm slidably guided in said cover.

In testimony whereof, we have hereunto 85 subscribed our names at Chicago, Cook County, Illinois.

FRED C. UTTERBACK.
